Francis J. Nekarda, Inventor,
By his Attorney,

W. B. Hutchinson.

UNITED STATES PATENT OFFICE.

FRANCIS J. NEKARDA, OF NEW YORK, N. Y.

SWIMMING AND LIFE-PRESERVING BELT.

1,315,190.

Specification of Letters Patent. Patented Sept. 2, 1919.

Application filed January 14, 1919. Serial No. 271,030.

To all whom it may concern:

Be it known that I, FRANCIS J. NEKARDA, a citizen of the United States, and a resident of the city, county, and State of New York, have invented a new and useful Improvement in Swimming and Life-Preserving Belts, of which the following is a full, clear, and exact description.

My invention relates to improvements in belts for supporting a person in the water so as to serve as a life preserver or as a support when one is swimming or learning to swim, and my invention is an improvement on the structure shown in Letters Patent of the United States No. 1,066,217, dated July 1st, 1913. In manufacturing and using the device of the patent referred to I have been able to improve certain details of construction which make the belt safer, more durable, more easily applied, and which enables the belt to be more easily inflated or deflated. The object of my present invention is to improve the structure referred to, and make the belt generally better for commercial use. These improvements will be pointed out later and will be clearly understood from the description which follows.

Reference is to be had to the accompanying drawings forming a part of this specification, in which similar reference characters indicate corresponding parts in all the views.

Figure 1 is a perspective view of the partly extended belt embodying my invention.

Fig. 2 is a broken side elevation of a part of the belt taken from the inner side.

Fig. 3 is a broken detail longitudinal section.

Fig. 4 is a detail showing how the outer and inner portions of the belt cover or fabric are united.

Fig. 5 is a broken end view showing how the fastening straps are secured to the belt.

Fig. 6 is a side elevation of the valve for controlling the inflation and deflation, the valve being shown in open position.

Fig. 7 is a side elevation of the valve in closed position and also showing its means of attachment to the end fabric of the belt, and

Fig. 8 is a cross section through the end valve with the valve aperture open.

55 The belt 10 is in general like the belt in the prior patent referred to in that it is a

hollow collapsible belt which can be closed up accordion fashion into a very small compass, thereby expelling the air, and which can be opened so as to permit the air to 60 rush in and inflate the belt, and can be readily fastened to the body. It has ribs 11 preferably like those shown in the former patent, these being spaced apart to give strength and shape to the belt, and the frame 65 formed by the ribs is covered by outer fabric 13, and an inside fabric 14 covering the flat side of the belt which comes next the body of the wearer. The meeting fabrics 13 and 14 are united along the inside 70 edges of the belt as shown at 15, and this in connection with the flattened inner sides of the ribs 11 gives a flat part which fits nicely against the body, and the middle portion is slightly narrowed as shown at 14^a in Fig. 75 2, this part corresponding to the portion which comes under the arms. I have found by practical experience that the outer fabric 13 cannot be made all in one piece without seriously straining the fabric, and in fact 80 the belt cannot be made to act properly and collapse and expand readily without strain unless it is made up in a series of segments 13 corresponding to the distance between the ribs 11 when the belt is expanded. The 85 meeting segments or sections 13 are united at their meeting edges as shown at 16, then at another point spaced apart as shown at 17, thus forming a channel 18 which receives the ribs, and in this way each in- 90 dividual section or segment 13 can be cut to the desired shape, fastened as specified, and united to the fabric 14 so as to form the sides of the belt, and the ends are closed by fabric 19 as shown. It will be understood 95 that the inclosing fabrics of the belt must be of water-proof material or of material which is water-proofed either before or after the belt is made, preferably the latter.

The belt is provided with end straps 20 100 and 21 attached respectively to the inner and outer edge portions of the belt, and these can be tied together in front of the wearer, or can be fastened in any other approved way. I have found, however, in practice 105 that where the straps are sewn or otherwise attached to the exterior of the belt they are quite likely to tear or become disengaged. To obviate this difficulty I wind the inner ends of the straps around the end ribs 11 110 and extend them out through the slit in the end fabric as shown in Fig. 5. This can

be easily done so as to make a water-tight closure, and in this way a very firm junction is made and the straps will last as long as the rest of the belt.

5 Experience has shown also that the belt is better for having an easily controlled valve at one end, and it might be at both ends of the belt. I have designed a valve connection which can be easily operated
 10 when the belt is on the wearer or when it is off, and while the invention is not limited to this form of valve, I prefer it. As shown in Figs. 6 to 8 the valve has a base or washer 23 which fits against the end fabric of the belt, and a similar washer 24 is placed against the inner side of the fabric, and the two washers riveted or otherwise fastened together. From the base or washer 23 rises an inner tube 25 which has apertures 26 therein, these apertures being preferably in the shape
 15 of an arrow head. An outer tube 27 incloses the inner tube and is preferably provided with a milled rim 28 which enables it to turn readily and it has openings 29 also preferably of arrow head shape which are adapted to register with the openings 26 of the inner tube. A pin 30 extends through the outer tube preferably through the milled part 28, and enters a transverse slot 31 in the inner tube which limits the movement of the outer tube and also causes the tube to hug snugly
 20 against the base 23, as the slot 31 is slightly inclined as shown in Fig. 6, and the slot is so placed that when the tube 27 is turned to the left to effect a closure, that is to bring the apertures 26 and 29 out of registry, the walls of the slot will exert a cam action on the pin and make a tight closure, and also prevent the tube from turning too readily, although so far as this is concerned the tubes
 25 can be made to fit very nicely one over the other.

The improvements which I have described while very simple are very important in the construction of a belt of this character, as
 30 they tend to make it safer, which is the first consideration, and also to make it stronger and generally better.

When the belt is not in use the end portions are simply pushed toward each other so as to collapse the tube which can be readily done if the valve at the end is open, as the air will be freely expelled from the

tube. When the belt is applied it is extended around the body beneath the arms, the straps 20 and the straps 21 fastened together, 55 and if the valve is open, the air, in sufficient volume to inflate the tube enough to make it support the weight of the wearer in the water, will rush in and the valve should be opened before the belt is applied and not 60 closed till the belt is adjusted. When it is applied the valve is closed by simply turning the tube 27, and obviously this can be very easily done. The atmospheric pressure will fill the belt sufficiently to support the 65 wearer because the ribs 11 prevent the belt from collapsing and hold it open to the free inrush of air. It will be noticed that the belt is rounded at the corners and that the longitudinal seams 15 are raised from the 70 flat side of the belt so that there are no sharp corners to hurt the wearer.

I claim:

1. As an improved article of manufacture, a belt of the character described comprising 75 a framework of ribs spaced apart and a fabric covering for the ribs, the outer portion of the fabric being made up in segments cut to the desired shape and fitting over the ribs at their meeting points. 80

2. A belt of the character described having a series of ribs spaced apart and flattened on their inner sides, and fabric covering for the ribs, the inner side of the belt being formed of a flat strip of fabric and 85 the outer portion being formed of separate segments cut to the desired shape and fastened together.

3. In a belt of the kind described the combination with the ribs, of the fabric covering formed of a series of segments united 90 at their edges and formed near said edges with channels through which the ribs extend.

4. A belt of the character described comprising ribs spaced apart, a fabric covering for the ribs, and fastening straps at the opposite ends of the belt, said straps being attached to the inner and outer portions of the belt ends and the inner ends of the straps 100 being wound around the end ribs. 95

FRANCIS J. NEKARDA.
